UNITED STATES PATENT OFFICE.

ALBERT WILLIS, OF COLUSA, CALIFORNIA.

BOAT-DETACHING APPARATUS.

SPECIFICATION forming part of Letters Patent No. 247,976, dated October 4, 1881.

Application filed July 5, 1881. (No model.)

To all whom it may concern:

Be it known that I, ALBERT WILLIS, of Colusa, in the county of Colusa and State of California, have invented certain useful Improvements in Boat-Detaching Apparatus, of which the following is a specification.

The object of my invention is to provide a new and improved device for lowering and detaching life-boats rapidly, safely, and in a simple manner.

The invention consists in an upright at each end of the life-boat, to the top of each of which uprights a short arm or beam is pivoted, the loose end of which passes into an aperture in a beam pivoted to the lower end of the upright, this upper beam being held in the aperture by a safety-chain and by a pintle passing through a ring attached to a string or chain fastened to the davit, so that when this string is drawn taut by the descending of the boat the ring pulls the pintle out of its aperture, so that the lower beam can drop when relieved of its strain—that is, when the boat floats—thus permitting the upper arm to swing upward and the ring of the pulley-block to slide from a hook on the upper pivoted beam, whereby the boat is detached from the pulley.

In the accompanying drawings, Figure 1 is a longitudinal sectional elevation of a boat provided with my improved detaching apparatus. Fig. 2 is a plan view of one of the uprights and the short arms or beams pivoted thereto.

Similar letters of reference indicate corresponding parts.

An upright, A, is firmly fastened in the bottom of the boat B at each end of the same, and a short beam or arm, C, having its free end rounded, is pivoted to the top of each beam A. A beam or arm, D, is pivoted to the bottom of each post or upright A, and the free end of this arm D is provided with an aperture, E, into which the rounded end of the arm C fits, these two arms being held together by means of a short safety-chain, F, attached to the upper end of the arm D, and by a pintle, G, attached to the end of the chain F, and passing through a ring, H, and into an aperture, J, in the beam C. This ring H is attached to a cord, chain, or equivalent, K, at-

tached to the davit O. A hook, L, extending toward the outer end of the arm C, is fastened on the upper surface of this arm. A ring, M, on the lower end of the pulley-block N is passed over this hook L, and the pulley-block is held to the post A by means of a safety-chain, P, attached to the block N, and by a staple, Q, attached to the end of the chain P and fitting in grooves R in the post A.

S is a cushion, block of rubber, or springs at 60 the foot of the upright A.

T are the ropes for lowering the boat.

The safety-chains can be dispensed with, if desired; but I prefer to use them, and if the device is not to work automatically the pulley-block can be attached in a different manner; but I prefer the construction described, the above remarks only serving as indications for possible modifications.

The operation is as follows: The rounded end of the arm C is passed into the aperture of the arm D, and is held in this position by the weight of the boat B, the arm C being slightly inclined downward, so that the ring M cannot slip from the hook L. As the boat is lowered the ring H, which is held to the davits by the cord K, draws the pintle G out of the aperture J; but this does not cause the arms C and D to separate, as the weight of the boat holds them in their position; but as soon as the boat B begins to float the strain is taken from the arm D, which drops, and the arm C is drawn upward, as shown on the right side of Fig. 1, permitting the ring M to slide from the hook L, whereby the boat is detached from the pulley. The cushion-block S prevents the arm D from dropping on the floor of the boat B and damaging the same.

This device operates automatically, and will not be released until the boat touches the water. The staple Q is drawn out of the grooves R as soon as the block M is separated from the beam C.

Having thus fully described my invention, I claim as new and desire to secure by Letters Patent—

1. The combination, with the lowering-tackle and uprights A, of the short arms C, with rounded ends pivoted to the top, and the arm D, with aperture E, pivoted to the bottoms of said up-

rights, the short chain F, and the pintle G, as shown and described.

2. In a boat lowering and detaching device, the combination, with the uprights A, of the arms C and D, provided with a rounded end and an aperture, respectively, and pivoted to the upright A of the pintle G, the ring H, the cord K, and of the boat-lowering tackle, substantially as herein shown and described, and for the purpose set forth.

3. In a boat lowering and detaching device, the combination, with the uprights A, of the

arms C and D, provided with a rounded end and an aperture, respectively, and pivoted to the upright A of the pintle G, the ring H, the cord K, the hook L, the ring M, the staple Q, the chain P, and the boat-lowering tackle, substantially as herein shown and described, and for the purpose set forth. 15

ALBERT WILLIS.
